UNITED STATES PATENT OFFICE.

JOHN S. FRENCH, OF SAN FRANCISCO, CALIFORNIA.

IMPROVEMENT IN ROCK-DRILLING MACHINES.

Specification forming part of Letters Patent No. 40,097, dated September 29, 1863.

To all whom it may concern:

Be it known that I, JOHN S. FRENCH, of San Francisco, in the county of San Francisco and State of California, have invented a new and Improved Rock-Drilling Machine; and I do hereby declare that the following is a full, clear, and exact description of the same, reference being had to the accompanying drawings, making a part of this specification, in which—

Figure 1 is a side sectional view of my invention taken in the line $x x$, Fig. 3; Fig. 2, a vertical section of the same taken in the line $y y$, Fig. 1; Fig. 3, a plan or top view of the same; Fig. 4, an enlarged detached front view of the mechanism which rotates the drill; Fig. 5, an enlarged detached longitudinal view of the mechanism which connects the drill with the draw-back slide.

This invention relates to a new and improved rock-drilling machine for tunneling and other purposes; and it consists in constructing and arranging the parts in such a manner that the drill may be turned and adjusted in either a vertical or a horizontal plane, so that holes may be bored in any desired direction—that is to say, either vertically, horizontally, or at any degree of inclination between said positions and at any point in a circle, the plane of which coincides or is parallel with the axis of the drill.

The invention further consists in a novel arrangement of means for operating the drill, whereby the same is drawn back from the hole after each stroke and turned while being drawn back, thus imitating or corresponding with the ordinary hand-manipulation of rock-drills, the blow being given the drill by means of a hammer operated by a cam and springs, as hereinafter fully set forth. The machine is placed or fitted upon a truck to enable the drill to be readily placed in position or adjusted to its work.

To enable those skilled in the art to fully understand and construct my invention, I will proceed to describe it.

A represents a truck, which may be constructed of wood, provided with two small wheels, $a a$, at one end, and two handles, $b b$, at its opposite, the whole being arranged in the same way as an ordinary hand-truck. On this truck there is permanently secured an annular plate, B, of metal, on which a metal

column, C, rests, said column having a plate, D, attached to its lower end, which is slotted longitudinally, as shown at e , and through which slot and the truck A a screw-bolt, E, passes, said screw-bolt being provided with a thumb-nut, d , to secure the plate D and column C in the desired position. By this arrangement it will be seen that the column C may be turned around on the plate B, and secured at any desired point thereon.

The column C is hollow and of rectangular form, and within it there is placed or fitted a block, F, of metal, through which a vertical screw, G, passes, said screw being rotated when necessary by means of bevel-gears e at its upper end in order to raise and lower the block F, which is allowed to slide freely in C.

H represents arms, which are secured to a horizontal pin, g , the latter passing through a vertical slot, h , in the column and into the block F, as shown clearly in Fig. 2. To this block F there is also attached a horizontal arm, i , which passes through a vertical slot, j , in the side of the column C opposite to the side in which the slot h is made, and on this arm the frame I of the drilling-machine is hung and allowed to turn freely. To the frame I there is secured a circle plate, J, which is concentric with the arm i , on which the frame I is hung. This circle plate J is provided with a flange, j , which extends all around its periphery, and has a lip, k , at one end of a bolt, l , passing over it, said bolt passing through the outer part of one of the arms H, and having a thumb-nut, m , upon it. By this arrangement it will be seen that the frame I may be turned on the arm i and secured at any point of an entire revolution thereon by screwing up the thumb-nut m , so that the lip k will clamp the flange j of the circle plate J. The frame I is raised and lowered by turning the screw G.

In the upper part of the frame I there is placed transversely a shaft, K, having a cam, L upon it and a crank, n . The cam L is simply a curved arm, as shown clearly in Fig. 1, and it works against a roller, o , at one end of an oblong slot, p , in a bar, M, which is arranged so as to slide in the upper part of the frame I. This bar M passes through the upper part of a swinging pendent arm, N, the upper end of which is attached to a rock-shaft, O, in the upper part of the framing I, and the

bar M has a stop, q, upon it, which catches against the arm N and draws it back in the direction indicated by arrow 1, when the cam L draws back the bar M. This stop q may be adjusted at different points on the bar M in order to regulate the extent of the swing of the arm N, as may be desired. The bar M each time it is relieved from the action of cam L has a forward motion given it by means of springs P, which may be of spiral or other form. To the lower end of the arm N a hammer, Q, is attached.

In the lower part of the frame I there is fitted a slide, R, which has a rack, r, on its upper surface, into which a pinion, s, gears, said pinion having a ratchet, t, attached to one side of it. Into the ratchet t a pawl, S, catches, which is operated from the crank n of shaft K.

To the slide R there are attached two spiral springs, u u, one at each side, and these springs are connected by cords v v to a shaft, w, which passes transversely through the lower part of the frame I, and has a ratchet, a', at one end, into which a holding-pawl, b', catches. (See Fig. 3.)

At the front end of the slide R there is an upright ledge, c', which has a semicircular recess made in its upper end to receive the lower part of a circular collar, d', on the drill T, the collar being allowed to turn freely in the recess in the ledge c'. The drill is of polygonal form, and it rests in a box, V, the interior of which where the drill rests being also of polygonal form. The exterior of box V is of cylindrical form, and is fitted in bearings e', so that it may rotate freely. The box is constructed of two longitudinal parts of equal size, and each of said parts has a half-bevel pinion, f', upon it, which form when in contact, and the two parts of the box are adjusted together, a whole pinion, into which a bevel-pinion, g', gears, the pinion g' having a ratchet, h', attached to it, into which a pawl, V, catches, which is attached to the pawl S at i'. (See Fig. 1.)

The two parts of the box V are held together in close contact by a clamp, W, which may be arranged in any proper way.

The operation of the drill is as follows: The shaft K may be rotated through the medium of any convenient power, and a swinging motion is given the hammer Q through the medium of the cam L, sliding bar M, and springs P, as previously referred to. Each time the hammer Q is drawn back the slide R is made to move back also, in consequence of the crank n, pawl S, ratchet t, pinion s, and rack r, and as the slide R is drawn back the drill T is drawn back with it, in consequence of the collar d' on the drill being fitted in the ledge c' on slide R. As the slide R moves back the drill T is rotated through the medium of the gearing f' g', the ratchet h', and pawl V. The pawl V receives its motion from the pawl S. When the pawl S loses its hold of the ratchet h', the springs u u force the drill T forward, and each time the cam L passes the roller o

the springs P will cause the hammer Q to strike the drill T.

Thus it will be seen that the drill is drawn back from the hole and turned each time it is drawn back, and when turned thrown forward into the hole and is then struck by the hammer Q, the operation so far as the working of the drill is concerned being precisely the same as the usual hand or manual working of rock-drills. The drill, as will, of course, be understood by the description previously given of the adjustment of the frame I, may be adjusted in a horizontal, vertical, or inclined position, according to the direction in which it may be required to work and at any time when a new or sharp drill requires to be inserted. The dull one is removed by releasing the clamp W from the box V and detaching one part of the latter, the sharp drill being fitted in the box V after the dull one is removed, and the clamp W adjusted again in proper position. This is but the work of a moment. The whole device may be readily moved from place to place, so that the machine may be adjusted in any desired position.

I would remark that the tension of the springs u u may be regulated as desired by turning or adjusting the shaft w.

Having thus described my invention, what I claim as new, and desire to secure by Letters Patent, is—

1. The manner of arranging the frame I of the machine so that it, and consequently the drill T, may be adjusted in either a vertical or horizontal position or at any degree of inclination between those positions and at any point in a circular plane parallel with the axis of the drill—to wit, by having the frame I hung loosely on an arm, i, which is attached to a block or nut, F, fitted in a vertical column, C, having a screw, G, placed in it, which passes through the block or nut and the column arranged to turn on a plate, B, on the truck A, the column being retained at any desired point, and also the frame I, by the means herein described, or their equivalents.

2. The drawing back of the drill T after each stroke by means of the slide R, connected with the drill through the medium of the collar d', fitting in the ledge c' on the slide, the slide being operated by the rack r', pinion s, pawl S, and crank n on shaft K, and springs u u, or their equivalents, as set forth.

3. Rotating or turning the drill T during its backward movement by means of the box V, gearing f' g', ratchet h', and pawl V, attached to the pawl S, substantially as set forth.

4. Operating the hammer Q through the medium of the cam L, slide bar M, and springs P P, substantially as specified.

Witnesses: JOHN S. FRENCH.

THOS. S. J. DOUGLAS,

A. R. HAIGHT.
